CLAIM

The ornamental design for a computer, as shown and described.

DESCRIPTION

FIG. 1 is a front perspective view of a computer showing our new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a front perspective view of the computer of FIGS. 1-7 shown without surface shading and disclaimed regions;

FIG. 9 is a top view thereof;

FIG. 10 is a bottom view thereof;

FIG. 11 is a right side view thereof;

FIG. 12 is a left side view thereof;

FIG. 13 is a front view thereof; and,

FIG. 14 is a rear view thereof.

The broken line showing of the various unshaded elements of the computer in FIGS. 1-7 illustrates environmental structure and forms no part of the claimed design.

1 Claim, 14 Drawing Sheets
